J. M. WHITE,
COMBINATION TOBACCO BOX,
APPLICATION FILED JULY 20, 1914.

1,141,027.

Patented May 25, 1915.

UNITED STATES PATENT OFFICE.

JAMES M. WHITE, OF DANVILLE, VIRGINIA.

COMBINATION TOBACCO-BOX.

1,141,027.

Specification of Letters Patent. Patented May 25, 1915.

Application filed July 20, 1914. Serial No. 852,912.

To all whom it may concern:

Be it known that I, JAMES M. WHITE, a citizen of the United States, residing at Danville, in the county of Pittsylvania and State of Virginia, have invented certain new and useful Improvements in Combination Tobacco-Boxes, of which the following is a specification.

The present invention appertains to improvements in that class of receptacles designed as pocket size containers for tobacco, the object in view being to provide an auxiliary compartment in the receptacle for holding matches, coöperating in a novel manner with a cover member for said receptacle.

I am aware that it has heretofore been proposed to construct a tobacco box with a main tobacco compartment and an auxiliary compartment for matches and therefore the essence of my invention lies more particularly in the special arrangement which eliminates any radical change in the form of construction of the ordinary tobacco box at present in general use, important from a manufacturing standpoint as well as from that of practical utility. With this in view I provide the receptacle body with an auxiliary cap member constituting the match compartment, superimposed upon the regular cap member for the container, utilizing a common hinge connection as well as a common locking element for these parts.

These and such other objects as may hereinafter appear are attained by the novel construction, combination and arrangement of parts to be hereinafter specifically described and claimed.

Reference will now be had to the accompanying drawings forming a part of this specification, wherein:

Figure 1 is a perspective view of a container constructed in accordance with my invention; Fig. 2 is an end view partly broken away and shown in section; Fig. 3 is a fragmentary front elevation of the box, partly broken away and shown in section; Fig. 4 is a fragmentary sectional view on the line 4-4 of Fig. 3; Fig. 5 is a similar sectional view taken substantially on the plane indicated by the line 5-5 of Fig. 3 but disclosing a slightly modified form of cover member for the receptacle body; and Fig. 6 is a fragmentary horizontal sectional view on the line 6-6 of Fig. 5.

Referring to the drawings, the numeral 1 represents the body portion of a receptacle stamped from sheet metal and formed in the conventional manner as the main compartment for holding tobacco. The upper portion of the body is provided with the usual stop bead 2 limiting movement of the cover member 3 secured to the body 1 at one of its longitudinal edges. It will be observed by reference to this figure that the cover 3 is formed in the usual manner from a single piece of sheet metal disposed so as to allow said cover member to be moved over the upper extremity of the receptacle body forming a complete closure for the main compartment of the receptacle. The cover 3 is preferably cut so as to provide the usual hinge loops or eyes 3' through which the pintle 4 is inserted to hingedly connect said cover to the receptacle body 1. At the opposite side of the cover the material is so cut as to leave an integral lip 5 which is bent back against the cover, and preferably rolled at its extremity in an outward direction, so as to form a locking member. The lip furthermore is provided with a detent 5' which is adapted to engage with a depression in the corresponding longitudinal edge of the body of the receptacle as indicated at 6 so as to constitute a positive interlocking connection between the cover and the body portion. The receptacle is also provided with a cap member 7 of sufficient size or depth, relatively speaking, to form an auxiliary compartment in which matches may be placed for the purpose of convenience in an article of this character. The cap member 7 at one of its longitudinal edges is cut so as to form a loop or eye 7' through which passes the pintle 4, said loop being interposed between the loops 3' for the cover 3 hereinbefore mentioned. In this manner a common hinge connection is provided for both the cap and cover members and when the cap member is in its normal closed position superimposed upon the cover 3 its longitudinal edge opposite its hinge connection is received between the flanged edge and the rebent lip 5 of the cover engaging over the top of the receptacle 1 and in this manner a frictional locking engagement is provided between the cover and said cap. Thus also is a common locking element provided for both of these parts.

It will be apparent from the foregoing

description that it is not necessary to depart from the usual construction of tobacco container which is now in common use, the cap member being connected to the receptacle and of a size sufficient to be imposed over the regular cover member for the tobacco box. The common connection intermediate the cap, the cover and the receptacle permits of the cover member being moved with the cap or the auxiliary compartment containing the matches in a manner shown most clearly by dotted lines in Fig. 4, thus enabling the tobacco to be extracted from the main tobacco compartment. It is only then necessary by pressing against the locking member 5 to close the cover member 3 over the tobacco compartment to enable access to the matches disposed in the auxiliary compartment or cap 7. The independence of these two members, the cap and the cover, is a very essential feature of my invention because it enables the user of the device to gain access to either of the compartments without likelihood of spilling the matches from the auxiliary compartment, as in practical use the cap and cover are simultaneously moved by pressing upwardly upon the catch member 5 when the parts are in their normal position as shown in Fig. 2.

The desirability of constructing the tobacco box with the usual type of cover member 3 fitting over the upper extremity of the tobacco compartment is evident because of the fact that said cover member effectively seals the tobacco compartment and prevents any of the moisture from the tobacco from affecting the matches in the match compartment. This cover, of course, constitutes a closure 4 or partition member intermediate the two compartments. However, in Figs. 5 and 6 I have shown a slightly modified form of cover member wherein the usual flange portions are omitted, said cover member being in the form of a flat plate 3^a which is adapted to rest upon the upper edges of the receptacle body 1 when in closed position. The material of the plate 3^a is so cut, however, as to leave a sufficient amount to form the hinge connection 3^b at one side and at the other side to form the rebent catch member or locking element 5^a. The construction of the cap member 7 in this form is exactly the same as that with reference to the preferred construction excepting that it fits snugly about the upper extremity of the box receptacle instead of telescoping over the flanges of the preferred form of cover member 3.

It will be evident that the construction may be cheaply manufactured and will constitute an attractive novelty by reason of its combination.

With this character of construction it is quite feasible to seal the tobacco compartment in the manner indicated in Fig. 1 so as to enable the marketing of the device without providing the auxiliary compartment with matches at the factory. The auxiliary compartment may, however, be filled and the seal placed over the top of the cap so as to simultaneously seal both compartments of the container.

Having thus described the invention, what is claimed as new is:

1. A receptacle of the class described comprising a main compartment, a cap member constituting an auxiliary compartment, a cover intermediate the receptacle and the cap member and forming a closure for both the main and auxiliary compartments, a hinged connection at one side of the receptacle common to said cap and cover members, and a locking member at the other side of said receptacle also common to said cap and cover members, said locking member constituting manipulating means operable on pressure thereagainst in one direction to open the main compartment and to release the cover member upon pressure thereagainst in the opposite direction disengaging the cover from the cap member.

2. A receptacle of the class described comprising a main compartment, a cap member constituting an auxiliary compartment, a cover intermediate the receptacle and the cap member and forming a closure common to both the main and auxiliary compartments, a hinge connection at one side for the cap and cover members, and locking means common to said members comprising an extension of the cover bent back thereagainst to receive and clamp the cover between the bent portion and the body of the cover.

3. A receptacle of the class described comprising a main compartment, a cap member constituting an auxiliary compartment, a cover intermediate the receptacle and the cap member and forming a closure common to both the main and auxiliary compartments, a hinge connection at one side for the cap and cover members, and a locking member for said cover member forming a lip extending from the cover, said lip being bent back against the cover member to form a spring clamp to lockingly engage the cap member, the lip being also formed with an interlocking detent adapted to engage the receptacle body.

4. A receptacle of the class described comprising a main compartment open at one end, a cover member formed with a depending flange adapted to fit over the open end of the main compartment, said cover member having its material cut at one flange edge to form an extension, said extension being bent back against the flange so as to constitute a locking lip, a detent formed in said lip adapted to engage the body of the

receptacle, a cap member connected to the body at one side and formed with a flange surrounding the same, said flange being of sufficient width to constitute an auxiliary compartment, the flange of said cap member being engageable in the bent lip extension of the cover member to lock the same in closed position, and a hinge connection common to

both the cap and cover members at the corresponding side of the receptacle.

In testimony whereof I affix my signature in presence of two witnesses.

JAMES M. WHITE.
